UNITED STATES PATENT OFFICE.

AXEL MALM, OF DAYTON, OHIO, ASSIGNOR TO THE EGRY REGISTER COMPANY, OF DAYTON, OHIO, A CORPORATION OF OHIO.

FOLDING-MACHINE.

1,142,828.

Specification of Letters Patent. Patented June 15, 1915.

Application filed December 2, 1912. Serial No. 734,486.

To all whom it may concern:

Be it known that I, AXEL MALM, a citizen of the United States, residing at Dayton, in the county of Montgomery and State of Ohio, have invented certain new and useful 5 Improvements in Folding-Machines, of which the following is a specification, reference being had therein to the accompanying drawing.

10 This invention relates to folding machines.

The object of the same is to provide a machine which will form a continuous longitudinal fold in a web of paper or similar material; which will operate at a high rate 15 of speed; which can be adjusted to form the fold along different longitudinal lines; and which will form the fold accurately along the line to which it is adjusted.

The present invention is designed more 20 particularly for folding paper for use in manifolding machines where three or more sheets are usually arranged one upon the other to provide a corresponding number of copies of the record that is made.

25 It is, therefore, a further object of the invention to provide a machine which will form a plurality of folds in a web of paper, arranging the several portions of the web accurately one upon the other.

30 A further object of the invention is to provide means for rewinding the folded web; and further to provide the machine as a whole and the several parts thereof of a simple, durable construction which will not 35 be easily disarranged or rendered inoperative.

In the accompanying drawings, Figure 1 is a side elevation of a machine embodying my invention; Fig. 2 is a rear elevation of 40 the same; Fig. 3 is a top, plan view of the same; Fig. 4 is a detail view of the adjusting device for the paper roll; Fig. 5 is a detail view of the tension device for the paper roll; Fig. 6 is a detail sectional view of the 45 friction drive for the rewinding reel; Fig. 7 is a sectional end elevation of the rewinding reel; Fig. 8 is a broken view of the rewinding reel showing the tube fastening device; Fig. 9 is a plan view of one pair of the folding rollers; and Fig. 10 is an end elevation of the same.

In these drawings I have illustrated one embodiment of my invention and have shown the same as comprising a main frame 1 55 which, in the present instance, is approxi-

mately square and of a height much greater than its length and breadth. This frame is provided, preferably near its upper end, with a support for a web of paper. The paper which is to be folded usually comes from a 60 printing press where blank forms have been printed thereon and is usually in the form of a roll. Therefore, I have here shown the web-supporting device as comprising a shaft 2 rotatably mounted on transverse frame 65 members 3 and adapted to extend through a roll of paper, such as indicated at 4. The web of paper is adjustable longitudinally on the shaft to position the same with reference to the folding devices proper and to cause a 70 fold to be made along the desired longitudinal line. As here shown, the roll is adjusted so that the line along which the fold is made is spaced from one edge of the web a distance equal to exactly one-third of the width 75 of the web. While the adjustment of the roll along the shaft may be accomplished in various ways a very simple method of accomplishing this is by adjusting the tapered cores 5, which are mounted on the shaft 2, 80 extend into the ends of the roll and are rigidly secured to the shaft to secure the roll in position thereon. With this adjustment it is possible to place the roll in any desired 85 position but it is rather difficult to secure fine adjustments thereof and I have, therefore, provided means for making finer adjustments of the paper roll. To this end I have rigidly secured to one end of the shaft 2, which extends beyond the frame member 90 3, a collar 6 having an annular groove 7 adapted to receive a finger 8 carried by a sleeve 9 journaled on a short shaft 10, one end of which is screw-threaded, as indicated at 11 and mounted in a screw-threaded opening 12 in the frame member 3. The shaft 10 is provided with a hand wheel or other gripping device 13 by means of which it 95 may be rotated and thus adjusted longitudinally with relation to the frame member 3. 100 The sleeve 9 is confined between the hand wheel 13 and a collar 14 rigidly secured to the shaft and is thus caused to move with the shaft, thereby imparting a corresponding movement to the collar 6 and the shaft 2 to 105 which it is secured. The sleeve 9 is held against twisting or binding by an arm 15 extending from that side thereof opposite the finger 8 and having an opening to receive a rod 16 projecting from the frame member 110

3. It is desirable that the paper should be subjected to a suitable tension to prevent the same from unwinding too rapidly. For this purpose a suitable band brake has been provided and I have utilized the drum 6 of the adjusting device for the drum of the brake. A flexible band 17 is rigidly secured at one end to the lower side of the sleeve 9, extends about the drum 6 and is secured at its upper end to a bolt 18 having a screw-threaded portion extending through an arm 19 rigidly secured to and projecting upwardly from the sleeve 9. A thumb nut 20 is mounted on the screw-threaded end of the bolt 18 and serves to adjust the same to tighten or loosen the tension band 17.

The folding device proper comprises a guide plate shaped to form the initial fold in the web and folding rollers to complete the fold. In the present embodiment of the invention the folding rollers, which are shown at 21, are journaled in transverse members 22 of the frame 1 and extend at substantially right angles to the web-supporting shaft 2. These rollers are adjustable along the supporting frame members 22 to enable them to be properly positioned with reference to the web of paper and to the coöperating folding devices. As here shown the supporting frame members are provided with longitudinal slots 23 and the rollers are provided with bearing blocks 24 and 25, respectively, slidably mounted in the slots. The bearing blocks 25 have clamping plates 26 secured thereto by means of bolts 27 and overlapping the edges of the groove, whereby the bearing blocks 25 may be rigidly secured in adjusted positions. Preferably, one of the rollers is yieldably mounted with reference to the other roller, and, to that end, the bearing blocks 24 of the other roller are movably mounted in the slots 23 and said other roller is held in proper relation to the first-mentioned roller by means of springs 28 contained between the bearing blocks 24 and blocks 29 adjustably mounted in the slots 23 and secured in position therein by means of clamping plates 30 and bolts 31. One of the rollers is provided with a pulley 32 driven by a belt 33 from a suitable source of power which will be hereinafter described, and the two rollers are connected one to the other by means of gears 34, whereby they are caused to move in unison in opposite directions.

The guide or folding plate, which forms the initial fold in the web of paper, is interposed between the support for the web of paper and the folding rollers 21 and has a portion tapered to a point, which point terminates close to the folding rollers 21 and is arranged substantially in the vertical plane extending between the adjacent surfaces of said rollers. In the present instance this folding plate, which is shown at 35, is triangular in shape and has its flat surface

arranged at an inclination to the horizontal plane of the folding rollers, as clearly shown in Fig. 1. This inclination of the plate preferably corresponds substantially to the angle formed by the converging edges of the plate which, as stated, taper to a point. The folding plate 35 is adjustably supported by means of an arm 36 which is rigidly secured thereto at a point between its upper and lower ends and extends rearwardly and then upwardly and is secured at its upper end to a transverse bar 37 which is adjustably mounted in vertical slots 38 formed in the adjacent vertical members of the main frame 1. If desired, a second arm 39 may project from the upper portion of the plate and be connected with the bar 37 to impart greater rigidity to the folding plate. An arm 40 is adjustably secured to the rearwardly projecting portion of the arm 36 and extends rearwardly and downwardly and is rigidly secured at its lower end to the rear frame member 22. The adjustable connection between the arms 40 and 36 may be of any suitable character but is here shown as formed by providing the arm 40 with a slot 41 and connecting the same to the arm 36 by means of a bolt 42. It will be obvious that by loosening the bolt 42 and adjusting the bar 37 vertically in the slots 38 the inclination of the folding plate 35 may be varied, it being understood that the ends of the bar 37, which extend through the slots, are rounded to permit the bar to accommodate itself to the varying inclinations of the plate. The arm 40 holds the bar 36 and the apex of the plate against vertical movement toward or away from the rollers, thus enabling the plate to be adjusted without materially altering the relation of the apex of the plate to the rollers. The folding plate is provided at its upper edge with a guide, such as a roller 43, to protect the paper as it passes over the edge thereof.

In order that the paper may pass properly over the upper end of the folding plate a guide roller 44 is mounted in the upper portions of the vertical frame members and the web of paper is carried from the paper roll across the upper end of the folding plate by the roller 44, thence upward and over the roller 43 which is carried by the upper edge of the folding plate. Preferably, the roller 44 is positively driven and has also the function of a feeding roller. To this end it is provided with a pulley 45 which is actuated by a belt 46 extending over an idler or belt tightener 47 and about a pulley 48 on the drive shaft to be hereinafter described. The paper passes down over the inclined face of the folding plate and is turned downward about the inclined or tapered edges of the plate with the apex of the plate at the line where it is desired to make the fold. In this manner the initial

fold is made and the two portions of the paper are arranged side by side, in which position they pass between the folding rollers 21. Preferably, the apex of the folding plate 5 lies close to and in the plane of the adjacent surfaces of the folding rollers. Thus, the paper passes directly from the plate to the rollers and the fold is completed and a distinct crease formed by these rollers. If 10 a single fold only is to be formed in the paper the operation is now completed, but the present machine is designed for forming a double fold and arranging the three portions of the web one upon the other. Therefore, a second folding device substantially 15 similar to that just described is provided. This second device comprises a pair of folding rollers 49 arranged at right angles to the folding rollers 21 and some distance below the same. These rollers are connected one to the other and are driven from a pulley 50 in substantially the same manner as the rollers 21 are connected and driven. An inclined tapered folding plate 51 is adjustably supported between the rollers 21 and the rollers 49 with its apex in the vertical plane extending between the adjacent surfaces of the rollers 49. The folding plate 51 is free at its upper and lower edges and 20 is supported by means of an arm 52 connected thereto between its ends and secured to a bar 53 adjustably mounted in a slotted frame member 54. The web of paper passes from the folding rollers 21 downward between a pair of feeding rollers 55 mounted in the slotted frame members 54. These feeding rollers are adjustably mounted in substantially the same manner as are the folding rollers 21 and are connected one to 25 the other in a similar manner. One of the rollers is provided with a bevel gear 56 meshing with a corresponding gear 57 on a shaft 58 having at its opposite end a gear 59 connected through an idle gear 60 with 30 a gear 61 on the driving shaft 62. The folded web of paper passes from the feeding rollers 55 upward about the upper end of the folding plate 51 and thence downward between the folding rollers 49 which complete the double fold. The folded web of 35 paper passes from the lower folding rollers 49 between positively driven feeding rollers 63 to a rewinding reel or drum 64. The rollers 63 are adjustably mounted in a slotted frame member 65 and one of them is provided with a sprocket wheel 66 which is driven by a sprocket chain 67 from a sprocket wheel 68 on the driving shaft 62. The folded web of paper might pass directly 40 from the feeding rollers 63 to the reel 64 but I prefer, particularly with the form of reel here shown, to cause the same to pass about guide rods to impose a certain amount of friction thereon and thus facilitate the proper rewinding thereof. I have, there-

fore, provided two such guide bars, which are shown at 69 and 70, respectively, and about which the paper passes before it reaches the reel.

The rewinding device comprises a shaft 71 having thereon a pulley 72 by means of which it is positively driven through a belt 73 from a corresponding pulley 74 on the positively driven feed roller 63. The reel 64 comprises an oblong drum or reel proper 75 having at one end a flange 76. This oblong drum is designed to receive a tube of cardboard or other suitable material which forms a core upon which the folded paper is rewound. This core is preferably 80 formed directly upon the drum by folding a strip of cardboard about the same and pasting the ends together, as indicated at 77. To hold the core against movement on the drum 75 a gripping device is provided 85 which comprises a plunger 78 carried by an enlarged nut or hand grip 79 which is screw-threaded onto a stud 80 mounted within the drum 75. The point of the plunger is arranged in alinement with an opening 81 in the opposite side of the drum 75 and by rotating the same the point may be caused to project through the opening in the drum and engage the core which has been formed on the same, thus holding the core 90 against longitudinal movement until it is desired to remove it therefrom. The oblong shape of the rewinding reel causes the paper to be wound snugly about the same, but to prevent the shock caused by the engagement 95 of the end portions of the reel with the paper from being too great and injuring the web I prefer to interpose a friction device between the drum and the driving mechanism. To this end I have rigidly secured 100 to the driving pulley 72 a friction disk 82 which co-operates with a corresponding friction disk 83 rigidly secured to the shaft 71 adjacent to the rewinding drum. The friction is controlled by means of a nut 84 and a spring 85 confined between the nut and the pulley 72.

The machine may be driven from any suitable source of power and as here shown the driving shaft 62 is provided with a driving 115 pulley 86 to receive the power belt and with a belt shifting device 87 to shift the belt from the power pulley to an idle pulley 88 and vice versa, this belt shifting device being provided with a handle or lever 89 by 120 means of which it may be actuated from the front of the machine. A hand wheel 90 is mounted on the power shaft to enable the mechanism to be rotated by hand during the threading up process, that is, when a web of 125 paper is being started through the machine.

The operation of the mechanism will be readily understood from the foregoing description and it will be apparent that the web of paper may be drawn through the ma- 130

chine at a relatively high rate of speed and that the fold will be accurately formed along the desired longitudinal line; and further, that the parts may be adjusted to form the 5 fold or folds along different lines.

While I have shown and described one embodiment of my invention it will be understood that this has been chosen for the purpose of illustration only and that I do not 10 desire to be limited to the details of construction shown and described, for obvious modifications will occur to a person skilled in the art.

Having thus fully described my invention, 15 what I claim as new and desire to secure by Letters Patent, is:—

1. A machine of the character described comprising a frame, means for supporting a roll of paper on said frame and for adjusting the same axially of said support, a triangular folding plate having its base adjacent to said roll of paper and substantially parallel with the axis thereof, a pair of folding rollers arranged near the apex of said 25 triangular plate, extending transversely to the axis of said roll of paper and adjustable in a direction parallel with the axis of said roll of paper and transversely to the apex of said triangular plate, said folding plate being arranged at an inclination to said folding rollers, and means for positively feeding the paper from said roll, over said plate and through said folding rollers.

2. A machine of the character described comprising a frame, means for supporting a roll of paper on said frame and for adjusting the same axially of said support, a triangular folding plate having its base adjacent to said roll of paper and substantially parallel with the axis thereof, a pair of folding rollers arranged near the apex of said triangular plate, extending transversely to the axis of said roll of paper and adjustable in a direction parallel with the axis of said 45 roll of paper and transversely to the apex of said triangular plate, said folding plate being arranged at an inclination to said folding rollers, means to adjust the inclination of said folding plate and to maintain the 50 apex thereof in proper relation to said folding rollers when adjusted to different angles, and means to feed the paper from said roll over said folding plate between said folding rollers.

3. A machine of the character described comprising a frame, a support for a web of paper carried by said frame, a pair of folding rollers arranged adjacent to said support, an inclined tapered folding plate interposed between said support and said folding rollers and having its apex close to the adjacent surfaces of said folding rollers, means to adjust the angle of inclination of said folding plate and maintain the same in 65 proper relation to said folding rollers when

adjusted to different angles, a feeding device arranged beyond said folding rollers, and a rewinding device arranged beyond said feeding device.

4. A machine of the character described 70 comprising a frame, means to support a web of paper in adjusted positions on said frame, a folding plate having two of its edges converging away from said support for said web of paper, a pair of folding rollers adjustably mounted adjacent to said plate and arranged to receive the web of paper from said folding plate, said folding plate being arranged at an inclination to said rollers, a bar mounted on said frame for adjustment toward and away from said rollers, and a connection between said folding plate and said bar.

5. A machine of the character described 75 comprising an upright frame, a support for a web of paper mounted on said frame near the upper end thereof, a pair of folding rollers arranged on said frame below said support, an inclined tapered folding plate interposed between said support and said folding rollers and having its apex arranged close to the adjacent surfaces of said rollers, a bar mounted for vertical adjustment on said frame, and a connection between said bar and said folding plate.

6. A machine of the character described 80 comprising a frame, a support for a web of paper carried by said frame, a pair of folding rollers arranged to receive the paper after it leaves said support, a bar adjustably mounted on said frame, an inclined tapered folding plate secured to said adjustable bar, interposed between said support and said folding rollers and having its apex close to the adjacent surfaces of said folding rollers, and means to limit the movement of said 85 plate toward said folding rollers.

7. A machine of the character described 90 comprising a frame, a support for a web of paper carried by said frame, a pair of folding rollers arranged to receive the paper after it leaves said support, a bar adjustably mounted on said frame, an inclined tapered folding plate secured to said adjustable bar, interposed between said support and said 95 folding rollers and having its apex close to the adjacent surfaces of said folding rollers, an arm arranged parallel with said folding rollers, and a connection between said plate and said arm to permit the plate to move 100 lengthwise of the arm and to limit its movement toward said folding rollers.

8. In a machine of the character described, 105 a main frame, a shaft rotatably mounted on said main frame near the top thereof and adapted to support a roll of paper, a pair of folding rollers arranged below said shaft and at right angles thereto, a triangular folding plate having one edge arranged parallel with said shaft and having its apex 110

adjacent to said folding rollers and arranged substantially in the vertical plane passing between the same, a bar mounted for vertical adjustment on said frame, means for connecting said folding plate with said bar, and a rewinding device arranged beyond said folding rollers.

9. In a machine of the character described, a main frame, a shaft rotatably mounted on said main frame near the top thereof and adapted to support a roll of paper, a pair of folding rollers arranged below said shaft and at right angles thereto, a triangular folding plate having one edge arranged parallel with said shaft and having its apex adjacent to said folding rollers and arranged substantially in the vertical plane passing between the same, a bar mounted for vertical adjustment on said frame, an arm rigidly secured to said folding plate between its ends and connected to said adjustable bar, a second arm adjustably secured to the first-mentioned arm and having one end connected with a fixed part of said frame, and a rewinding device arranged beyond said folding rollers.

10. In a machine of the character described, the combination, with a frame, a shaft mounted on said frame and adapted to support a roll of paper, a pair of folding rollers arranged beneath said shaft and at right angles thereto, an inclined triangular folding plate interposed between said shaft and said folding rollers and having one edge substantially parallel with the adjacent edge of said folding plate, a second pair of folding rollers arranged below the first-mentioned folding rollers and at right angles thereto, an inclined tapered folding plate interposed between the two pairs of folding rollers and having one edge substantially parallel with the edge of said second folding plate, a pair of feeding rollers arranged beyond and substantially parallel with the last-mentioned pair of folding rollers, a rewinding device arranged beyond said last-mentioned feeding rollers, and means for driving said feeding rollers and said folding rollers in unison.

11. In a machine of the character described, the combination, with a frame, a shaft mounted on said frame and adapted to support a roll of paper, a pair of folding rollers arranged beneath said shaft and at right angles thereto, an inclined triangular folding plate interposed between said shaft and said folding rollers and having one edge substantially parallel with said shaft, a positively driven roll interposed between said shaft and said folding plate and arranged substantially parallel with the adjacent edge of said folding plate, a second pair of folding rollers arranged below the first-mentioned folding rollers and at right angles thereto, an inclined tapered folding plate interposed between the two pairs of folding rollers and having one edge substantially parallel with the first-mentioned pair of folding rollers, a pair of feeding rollers interposed between the first-mentioned pair of folding rollers and the second folding plate and arranged substantially parallel with the edge of said second folding plate, a pair of feeding rollers arranged beyond and substantially parallel with the last-mentioned pair of folding rollers, a rewinding device arranged beyond said last-mentioned feeding rollers, and means for driving said feeding rollers and said folding rollers in unison.

12. In a machine of the character described, a frame, a shaft mounted on said frame and adapted to support a roll of paper, means to adjust said roll of paper on said shaft and to longitudinally adjust said shaft relatively to said frame, a pair of folding rollers adjustably mounted on said frame beneath said shaft and at substantially right angles thereto, and an inclined tapered folding plate adjustably supported on said frame between said shaft and said folding rollers.

In testimony whereof, I affix my signature in presence of two witnesses.

AXEL MALM.
